CLAIM

The ornamental design for a paper product, as shown and described.

DESCRIPTION

FIG. 1 is a top plan view of a first embodiment of a paper product showing our new ornamental design it being understood that the inner perimeter of broken lines defines one repeat unit of the claimed design, which repeats uniformly throughout the length and width of the paper product. The outer perimeter of broken lines indicates that a specific length and width of the paper product forms no part of the claimed design; and,

FIG. 2 is a top plan view of the ornamental design of FIG. 1. The broken line showings are for illustrative purposes only and form no part of the claimed design. The broken lines shown along the border of the figures indicate that the design may repeat uniformly in one or more directions. The broken lines form no part of the claimed design.

The surfaces or portions not shown in the drawings or described in the specification form no part of the claimed design.
